UNITED STATES PATENT OFFICE.

EDWARD J. DAVIS, OF ROCHESTER, NEW YORK.

SAW-TABLE ATTACHMENT.

1,118,477.

Specification of Letters Patent. Patented Nov. 24, 1914.

Application filed July 10, 1912. Serial No. 708,585.

To all whom it may concern:

Be it known that I, EDWARD J. DAVIS, of Rochester, in the county of Monroe and State of New York, have invented certain new and useful Improvements in Saw-Table Attachments; and I do hereby declare the following to be a full, clear, and exact description of the same, reference being had to the accompanying drawings, forming a part of this specification, and to the reference-numerals marked thereon.

My invention relates to saw table attachments, and more particularly to guards for rotary saws, and it has for its object to provide an improved form of guard which is movable with the saw in its adjustment relatively to the saw table, and is also adjustable relatively to the saw.

A further object of my invention is to afford a removable portion on the guard, the same being normally held in interlocking engagement with the body portion of the guard, and means for enabling its ready removal when desired.

Still another object of my invention consists in affording means for preventing fine dust and shavings from being thrown in the face of the operator, as he stands in front of the saw table to control the work.

To these and other ends the invention consists in certain improvements and combinations of parts, all as will be hereinafter more fully described, the novel features being pointed out in the claim at the end of the specification.

In the drawings: Figure 1 is a vertical sectional view of a saw table, showing the application of a preferred embodiment of my invention thereto. Fig. 2 is a detail elevation of a portion of the saw guard; Fig. 3 is a sectional view on the line 3^a—3^a of Fig. 2. Fig. 4 is a sectional view on the line 4^a—4^a of Fig. 2, and Fig. 5 is a sectional view on the line 5^a—5^a of Fig. 2, showing a portion of the saw in section below the guard.

Similar reference numerals throughout the several views indicate the same parts.

In the present embodiment of the invention, 1 designates the saw table, and 2 is the saw, held in operative relation to the saw table on the support 3, which is mounted in any suitable manner and may be arranged to swing, if desired, for holding the saw at different elevations.

4 is a standard which is adjustably mount-

ed on the support 3. To this end, in the present embodiment, the standard 4 is provided with a base or attaching portion 5, slotted at 6, and held adjustably in engagement with the support 3, by means of bolts 7, or other suitable attaching means.

The guard comprises a body portion 8 which is slotted at 9 and held in adjustable relation to the standard 4 by means of bolts 10. In certain kinds of work, it is frequently desirable to leave the upper part of the saw free from obstruction by the guard, and to accomplish this, I provide a removable portion 11 which is normally held in engagement with the body portion 8 in the manner that I will now describe. The body portion 8 and the removable portion 11 have an interlocking connection with each other, preferably being dovetailed as shown in dotted lines in Figs. 1 and 2.

In order to hold the removable portion 11 in operative position on the body portion 8, the former carries a plate 12 which is suitably attached thereto and forms a downwardly extending flange 13 adapted to overlie a portion of one face of the body portion. On its opposite face, the removable portion 11 is provided with a catch 14, which is pivotally mounted at 15 and carries a thumb piece 16 by which it may be turned.

17 is a leaf spring, formed by being struck from the removable portion 11, and adapted to engage a shoulder on the catch 14, as shown in Fig. 1, whereby to hold the same in locking position, and prevent the removable portion being detached from the body portion. To release the removable portion, the spring 17 is depressed, permitting the catch to be turned, whereupon the removable portion 11 may be moved laterally of the body portion 8.

In order to protect the operator, and prevent dust and shavings from being thrown from the saw into his face, I provide a deflector on the guard. This is preferably accomplished in the present embodiment by means of flanges 18 which are secured to the removable portion 11, and extend outwardly and downwardly therefrom. This affords an inverted U-shaped device arranged immediately above the top of the saw, which serves to catch all of the fine dust and shavings that are thrown upwardly by the rotating movement of the saw. By this construction, it is possible for the operator to stand in front of the saw, in proper posi-

tion to control the work, without being subjected to the large amount of dust and dirt that is thrown off from saw tables as generally constructed.

5 In the claim:

In a fastening means, the combination with a body portion, of a removable portion having a dovetailed connection with the body portion, a swinging latch pivoted to

one face of the removable portion and 10 adapted to embrace the corresponding side of the body portion, and a flange on the opposite face of the removable portion arranged to overlie the body portion.

EDWARD J. DAVIS.
